[57] CLAIM

The ornamental design for a drywall marker, as shown and described.

DESCRIPTION

FIG. 1 is a top, front, and left side perspective view of a drywall marker showing our new design, the dotted line showing of a fragmented corner of a utility box is environmental only and forms no part of the claimed design;

FIG. 2 is a top plan view;

FIG. 3 is a bottom plan view;

FIG. 4 is a front elevational view;

FIG. 5 is a rear elevational view;

FIG. 6 is a top, front, and left side perspective view of a second embodiment of FIGS. 1-5 showing our new design;

FIG. 7 is a top plan view;

FIG. 8 is a bottom plan view;

FIG. 9 is a right side elevational view;

FIG. 10 is a rear elevational view;

FIG. 11 is a top, front, and right side perspective view of a third embodiment of FIGS. 1-5 showing our new design;

FIG. 12 is a top plan view;

FIG. 13 is a bottom plan view;

FIG. 14 is a right side elevational view;

FIG. 15 is a left side elevational view; and

FIG. 16 is a rear elevational view thereof.
